ORVILLE C. WRIGHT, OF FORT WAYNE, INDIANA.

LUBRICATOR FOR AIR-COMPRESSORS.

1,179,990.

Specification of Letters Patent. Patented Apr. 18, 1916.

Application filed March 10, 1915. Serial No. 13,492.

To all whom it may concern:

Be it known that I, ORVILLE C. WRIGHT, a citizen of the United States of America, and resident of Fort Wayne, in the county 5 of Allen and State of Indiana, have invented certain new and useful Improvements in Lubricators for Air-Compressors, of which the following is a specification.

This invention relates to improvements in 10 automatic lubricators for air-compressors and the manner of applying the same, and the objects are: first, to so construct the device and apply the same that its operation will occur simultaneously with the action 15 of the air-compressor with which it is connected; second, to so apply the device to the air-compressor that the piston of the former will be reciprocated by the alternate vacuum and pressure occurring in one end of the air- 20 compressor cylinder as the suction and subsequent compression takes place; and third, to provide means for feeding the lubricant at a definite rate to the steam cylinder 25 that drives the air-compressor as well as to the air-compressing cylinder.

A fourth object is to so construct the device that its operating parts will be contained within the case forming the oil reservoir.

30 The above objects are accomplished by the construction and arrangement illustrated in the accompanying drawings in which:—

Figure 1 is a front elevation of an air-compressor of the type commonly used on 35 locomotives, showing the device applied thereto and with a portion of the air-compressing cylinder cut away and in section; Fig. 2 is a similar elevation of the device shown partly cut away and in vertical section; and Fig. 3 is a detail view of the 40 reciprocating piston.

Similar characters of reference indicate corresponding parts throughout the several views and referring now to the same: (A) 45 is an air-compressor of the usual type having a steam cylinder (B) and air-compressing cylinder (C), the former having a steam supply pipe (D) and exhaust outlet (E), and the latter having a screened intake pipe 50 (F) and a discharge pipe (G).

The lubricator is comprised of a reservoir (H) having an integral bracket (J) that affords support for the device when attached to the lower end of the steam cylinder. A screen 55 (K) is arranged in the upper part of the

reservoir for straining the oil as it is introduced into the chamber (L), and a cap (M) is provided to close the reservoir at the top thereof.

Extending within the interior of the reservoir is an angular body (N) that has integral relation at its side with the side wall of the reservoir, and like relation at its lower end with the bottom thereof, and upon the exterior of the reservoir adjacent the juncture of the angular body and the side wall is a projecting threaded boss (O). The bottom of the reservoir (H) has made there-in aligned chambers (P) and (Q), the former being of greater diameter than the latter, 60 and coincident with the former, extending from the wall of the reservoir is a threaded-boss (R). A discharge port (S) leads from the chamber (P) through a boss (T) that extends from the bottom of the reservoir, 65 and leading into the chamber (Q) are two feed ports (U) and (V) respectively.

The body (N) has made therein aligned chambers (W) and (X) respectively, the former being of greater diameter than the latter and extending thereabove, and a port (Y) leads from the chamber (X) into the chamber (Q) in the bottom of the reservoir. Another port (Z) leads from the chamber (W) outwardly through the boss (O). A 70 screw plug (4) extends into the upper end of the body to close the top of the chamber (W). Within the chamber (W) is a ball-valve (5) adapted to close the upper end of the chamber (X) and within the latter chamber is a ball-valve (6) adapted to close the upper end of the port (Y), each valve being adapted to check the downward flow of lubricant passing through the chambers.

The driving member is comprised of a piston-head (7) having a recessed shank (8) extending from one end thereof, the recessed portion (9) being adjacent the head. When in place the shank (8) extends into the chamber (Q) while the head (7) extends within the larger chamber (P) and the member is adapted to be reciprocated therein. A compression spring (10) is arranged in the chamber (Q) and bears against the end of the shank (8) and serves to aid the movement of the driving member in its outward stroke. The driving member is so proportioned and the ports (U) and (V) are so placed that when the driving member 100

110

is at the limit of its inward stroke the port (U) will communicate with the recess (9) and the enlarged portion (8) of the shank will close the port (V). The discharge port (S) will also be closed by the piston-head (7).

When the driving member is at the limit of its outward stroke, the feed-port (V) will have communication with the chamber (Q), the feed port (U) will be closed, and the discharge port (S) will be open so that oil, received about the recess (9) may pass to the discharge port and become expelled. The recess (9) is made of such size that the required amount of lubricant is conveyed at each stroke of the driving member, and likewise the shank (8) is so proportioned and the feed-port (V) so placed that the desired amount of lubricant will be forced from the chamber (Q) out through the discharge port (Y) at each stroke of the driving member.

In operating the invention the boss (R) is connected by means of a pipe (12) with one end of the air-compressing cylinder as shown at (13); the boss (T) is connected by means of a pipe (14) with the intake pipe (F) of the air-compressing cylinder; and the boss (O) is connected by means of a pipe (15) with the steam feed pipe (D). As the air-compressor is operated, the driving member will become reciprocated, the outward stroke thereof being caused by the vacuum formed in the air-compressing cylinder during the intake of air in the upper part thereof, and the inward stroke being due to the subsequent compression that takes place in the upper part of the air-compressing cylinder. Thus, it will be understood that the driving member is reciprocated as the alternate vacuum and pressure is formed in the upper part of the air-compressing cylinder, and then only.

A quantity of lubricant in the reservoir will pass through the port (U) into the space within the chamber (Q) about the recess (9), and when the driving member is moved to its outward position the lubricant received about the recess will be carried into the chamber (P) and the port (U) will be closed and the discharge port (S) will be opened so that the lubricant may pass into the discharge port (S) from whence it is directed by the pipe (14) into the suction pipe of the air cylinder. While the driving member is in its outwardmost position, the port (V) will have communication with the chamber (Q) and the lubricant in the reservoir will pass thereto, and upon the inward movement of the driving member the lubricant will be forced up through the port (Y), past the ball-valves (6) and (5), and out through the discharge port (Z) from whence it becomes directed through the pipe (15) into the steam feed pipe (D).

Thus, a quantity of the lubricant from the reservoir is constantly introduced into the intake of both the steam and air cylinders of the compressor during the operation of the latter, and only then.

One of the features of this invention is that the lubricant is introduced into the steam feed pipe in a condition suitable for the lubrication of the steam cylinder, and into the air-compressing cylinder in a state 75 peculiarly adapted for its lubrication. In the former instance the oil entering the chamber (Q) through the feed port (V) is forced bodily past the check-valves and the connecting pipe (15) into the steam feed 80 pipe through which it is carried by the passing steam into the steam cylinder. The lubricant that enters the chamber (P) after passing into the recess (9) from the feed port (U) during the outward stroke of the 85 driving member is drawn into a nebulous state, which is partly due to vacuum formed within the chamber (P) after the enlarged portion of the shank (8) closes the feed port (U) and the subsequent relief of the vacuum thus formed by the opening of the discharge port (S). Upon the return inward stroke of the driving member immediately preceding the closure of the discharge port (S) by the piston head, a slight pressure carrying the nebularized lubricant occurs within the chamber (P) that drives the lubricant in the nebular state through the connecting pipe (14) into the suction pipe (F) of the air-compressing cylinder. Thus, the 100 lubricant is introduced into the air-compressing cylinder in a state best suited for its lubrication. The driving member and the chambers in which it operates and the arrangement of the feed ports and the discharge port that leads to the air-compressing cylinder are so proportioned and arranged to effect the condition of the lubricant as above stated.

By the construction herein disclosed the 113 device is made practically self-contained and with few parts, and furthermore the operating parts of the device being contained within the chambers made in the body of the reservoir forming the reservoir, obviates all 115 liability of derangement thereof from external causes.

What I claim is:—

1. In apparatus of the class described an air-compressor having a steam cylinder and 121 air-compressing cylinder, the steam cylinder having a steam feed pipe leading thereto and the air compressing cylinder having a suction pipe; a reservoir for liquid lubricant; a reciprocating driving member in 125 connection with the reservoir, the latter having ports for the admission of fluid from the reservoir to the driving member and having also discharge ports leading therefrom; a pipe connection between one 130

of said discharge ports and the steam feed pipe; a pipe connection between the other of said discharge ports and the suction pipe; and a pipe connection affording communication between one end of the air-compressing cylinder and the driving member, the latter being actuated in its reciprocal movements by the alternate vacuum and compression occurring within the said end 10 of the air-compressing cylinder.

2. In apparatus of the class described; an air compressor including a cylinder in which vacuum and pressure alternate and having a suction inlet; a chambered reservoir for liquid lubricant having feed and discharge ports, the latter having free communication with the suction inlet of the air-compressor; and a reciprocating driving member adapted to alternately close and 15 open said ports, one end of said cylinder having independent air communicating connection with the driving member.

3. In a device of the class described a reservoir having therein an integral member connecting its side wall and bottom, and having also made in its bottom alined chambers and two feed ports leading from the reservoir into one of said chambers and also a discharge port leading from the other of 20 said chambers, the integral member having a passage-way therethrough leading from the former chamber; a check valve within the integral member; and a driving member arranged within said chambers and 25 adapted to be reciprocated therein.

4. In an automatic lubricator a reservoir having an integral member connecting its bottom and side wall, the said member having a passage-way extending therethrough; 30 a reciprocating driving member arranged in suitable chambers made in the bottom of the reservoir, one of said chambers having communication with the opening in the integral member, and the other of said chambers 35 having a discharge port leading therefrom, the said reservoir having also feed ports leading into the former chamber; and means within the passage-way in the integral member to prevent back-flow of lubricant 40 passing therethrough.

5. In apparatus of the class described, in combination with an air compressor having a suction inlet, a reservoir adapted to contain a quantity of lubricant and having in 45 its lower part a chamber, there being also inlet and outlet ports communicating with the chamber therein, the outlet port having communicating means with the suction inlet of the air compressor; a reciprocating 50 driving member adapted to alternately close and open said ports; and means independent

of the ports for applying alternate pressure and vacuum to the driving member.

6. In apparatus of the class described a reservoir for lubricant having in the bottom 65 thereof chambers for a driving member, a reciprocating driving member operatively arranged in said chambers, said reservoir having feed openings communicating with one of said chambers and a discharge opening 70 leading from the same, there being also a discharge opening leading from the other of said chambers; and means for creating alternate vacuum and pressure and applying the same to the driving member. 75

7. A lubricating device comprised of a reservoir having in its bottom alined chambers for a driving member there being a discharge port leading from each chamber and also two feed ports leading into one of said 80 chambers; a driving member comprised of a piston head having a shank with a recess made therein immediately adjacent the piston head, said recess being adapted to receive lubricant from one of said feed ports 85 and convey the same to one of said discharge ports when the driving member is actuated, the said shank being adapted to force lubricant passing the other feed port out through the other of said discharge ports; and a 90 check valve to prevent back-flow of lubricant through the latter discharge port.

8. In a lubricator, a reservoir having chambers in the bottom thereof with feed ports affording communication therewith 95 and also discharge ports leading therefrom; a check valve for the discharge through one of said discharge ports; a driving member arranged in said chambers and being adapted to be reciprocated therein, the 100 shank of the driving member being adapted to open and close one of said feed ports and to force lubricant received therethrough out through one of said discharge ports, the shank of said driving member having a recess for the reception of lubricant from the other of said feed ports, the piston head of the driving member being adapted to open and close the other of said discharge ports, the latter feed port and discharge port being 105 so located that the former will become closed before the latter becomes opened; and means for applying alternate vacuum and pressure to the driving member to reciprocate the same. 110

In testimony whereof I affix my signature, in presence of two witnesses.
